UNITED STATES PATENT OFFICE.

ARISTIDES R. MURRAY, OF CINCINNATI, OHIO, ASSIGNOR TO THE CINCINNATI GEAR CUTTING MACHINE COMPANY, OF CINCINNATI, OHIO, A CORPORATION OF OHIO.

CUTTER-GRINDING MACHINE.

1,148,525.

Specification of Letters Patent.

Patented Aug. 3, 1915.

Application filed September 23, 1914. Serial No. 863,116.

To all whom it may concern:

Be it known that I, ARISTIDES R. MURRAY, a citizen of the United States, residing at Cincinnati, in the county of Hamilton and 5 State of Ohio, have invented certain new and useful Improvements in Cutter-Grinding Machines, of which the following is a specification.

My invention relates to cutter grinding 10 machines for grinding for instance the cutters of milling machines, hobbing cutters, and the like, and applicable for grinding cutters, the cutting-faces of which it is desired to have extend in directions other than 15 parallel to the axis of rotation of the cutter. In hobbing cutters it is desirable to have the cutting-faces of proximate teeth extend in opposite directions out of parallelism with the axis of the cutter.

20 It is the object of my invention to provide means whereby the median lines of the cutting-faces of the teeth of cutters shall be maintained substantially radial of the cutter in grinding so that the cutting-faces at 25 each side of said median lines shall retreat equally for maintaining the contours of the cutting-edges of the teeth, whether said cutting-edges be plain, that is, parallel to the axis of rotation of the cutter, or staggered, 30 that is alternately sloping in different directions with relation to said axis, it being understood that such cutters are usually of the solid type and have relieved cutting-teeth.

35 It is a further object of my invention to provide novel means for presenting the cutter being ground at various angles to the grinding-wheel; and, further, to provide novel means for controlling the positions of 40 the cutter and its teeth during the grinding operation.

The invention will be further readily understood from the following description and claims, and from the drawings, in which 45 latter:

Figure 1 is a plan view of a cutter grinding machine exemplifying my invention. Fig. 2 is a front elevation of the same, partly broken away. Fig. 3 is a side elevation of 50 the same, partly broken away. Fig. 4 is a vertical cross-section taken on the line 4—4 of Fig. 1, showing the manner of mounting the cutter-slide, and showing the means for mounting the cutter-yoke in front end ele-

vation. Fig. 5 is a detail in section on the 55 line 5—5 of Fig. 1. Fig. 6 is a cross-section on the line 6—6 of Fig. 1, showing the manner of mounting the cutter-yoke. Fig. 7 is a plan view showing the gage in use for adjusting the cutter-supporting bracket laterally with relation to the grinding-face of 60 the grinding-wheel. Fig. 8 is a plan view showing a hobbing cutter in position and in relation for having one of its series of cutting faces ground by the grinding-wheel; 65 and, Fig. 9 is an inside end view of the same.

The means for mounting and reciprocating the cutter-slide and the means for mounting and driving the grinding-wheel, herein shown and described, are in the main 70 the same as shown, described and claimed in my application for Letters Patent on improvements in cutter grinding machines, filed November 7, 1913, Serial No. 799,747.

11 represents the frame of the machine 75 on which there is a refuse-pan 12. A grinding-wheel shaft 13 is journaled in bearings 14 of a hollow pillow 15 in the refuse-pan. The shaft 13 has a pulley 16 thereon for receiving a suitable belt passing through 80 the hollow of the pillow about the pulley. A grinding-wheel 17 is suitably releasably secured to the shaft 13, as by means of a nut 18. The grinding-wheel is shown as a cup-shaped wheel, the grinding-face 19 of the 85 wheel being at the outer end of the cup-wall thereof and extending in a plane at right angles to the axis of rotation of the grinding-wheel shaft. This grinding-face is maintained in its true plane if 90 necessary by redressing. A hood 20 is received about the upper portion of the grinding-wheel, and is pivoted to the refuse-pan by a pin 21. The fluid for the grinding-wheel is fed through a suitable spout 95 22, suitably secured to the hood.

23 is a cutter-support which, in the present exemplification, is mounted on a slide 24 and is adjustable laterally for positioning the cutter, shown at 25, laterally with 100 relation to the grinding-wheel. The slide exemplified comprises a slide-member 26, an apron 27 and a bracket 28. Guides 29 are provided between the slide-member and the shelf 30 of the apron. The guides are 105 suitably secured to the slide, the shelf having guideways 31 co-operating with the guides. One of the guides is provided with

rack-teeth 32, with which a pinion 33 on a removable adjusting stem 34 removably received in a bearing 35 in the shelf is arranged to mesh. Bolts 36 are threaded into the slide-member as shown at 37, and extend through slots 38 in the support, nuts 39 being threaded over the outer threaded ends of said bolts for clamping the cutter-support in laterally adjusted position to the slide-member, washers 40 being interposed between said nuts and the shelf. The slide-member is arranged to move back and forth on a guide 41, shown formed on the outer face of one of the side walls of the refuse-pan.

The apron 27 depends into the refuse-pan, the bracket 28 being pivoted to said apron by means of a shaft 45 which extends through a bearing 46 in the apron and through bearings 47 in the bracket, the shaft having a head 48 at one of its ends, its other end being screw-threaded, as shown at 49, a clamp-nut 50 being threaded to said threaded end for clamping the bracket in adjusted position between the apron and said nut. The apron and bracket have coacting slide-faces 51. A shifter-arm 52 is provided for shifting the bracket about the shaft 45. The angular positioning of the bracket about its rocking axis raises or lowers the tooth to be presented to the grinding-wheel for enabling the inner corners of the cutting-faces of the teeth at both sides of the usual webs between the bases of the teeth to be ground.

An extension 55 extends rearwardly from the bracket and has a back-stop 56 pivoted with relation thereto, the back-stop being arranged to contact the rear faces or backs of the teeth of the cutter for positioning the several teeth, respectively with relation to the grinding-wheel, so as to insure uniformity of grinding of the cutter-teeth. The back-stop is shown pivoted by a pin 57 to a collar 58 adjustable laterally on an arm 59, whereon it is clamped in adjusted positions by a clamp-screw 60, the arm being on a slide 61 adjustable back and forth on the extension 55 by means of T-bolts 62 adjustably placed in a T-slot 63 in said extension and clamped in adjusted positions by nuts 64, as more particularly described in my aforesaid application. The position of the back-stop may be further adjusted by means of an adjusting screw 65, and is normally held in obstructing position with relation to the teeth of the cutter by means of a spring 66, the back-stop receding from the advancing tooth of the cutter when the cutter is turned for placing the next advancing tooth in grinding position, and snapping back into obstructing position upon passage of said tooth, whereby the back of the tooth may be placed against said back-stop.

The cutter is arranged to be moved toward and from the grinding-wheel, as by providing the slide with a rack 71, with which a segment-gear 72 meshes, the segment-gear being on a rock-shaft 73 operable by an arm 74, stops 75, 76, controlling the limits of reciprocating movement of the slide and the cutter as more particularly shown, described and claimed in my aforesaid application.

The bracket 28 is provided with a bearing 81 in which the cutter-support 23 is rockable. The cutter-support is shown as provided with a journal 83 in the bearing 81, there being a gage 84 between said cutter-support and bearing for gaging the angularity of the adjustment between said cutter-support and bearing. The graduations 85 of the gage are shown on the cutter-support and are arranged to register with a guide-mark 86 on the bearing. The bearing is shown as a clamp-bearing arranged to be clamped about the journal by means of a clamp-screw 87.

The cutter-support is shown as of yoke 90 form, being provided with tines 88, 89, for supporting a cutter-stem 90, which is received through the bore 91 of the cutter to be ground, one or more bushings, one of which is shown at 92, being placed about the stem when necessary for centering the cutter about said stem. The stem is so placed on the support that its longitudinal axis is intersected by the rocking axis of the cutter-support.

The parts are so arranged that when grinding the cutting-faces of teeth of plain-tooth cutters, the cutting-face of the tooth being ground will lie in a plane parallel to the longitudinal axis of the stem coincident with the rocking axis of the support when the guide and zero marks of the gage register with each other. This cutting-face of the tooth being ground is further caused to lie in the plane of the grinding face of the grinding-wheel by lateral adjustment of the bracket 28.

The cutter is further adjustable in directions parallel to its axis of rotation so as to adjust the same for placing the middle of the width of the cutting faces of its teeth in a plane which extends at right angles to the axis of rotation of the cutter and is coincident with the rocking axis of the cutter-support. Said rocking axis is in line with the grinding-face of said grinding-wheel, when the cutter-support has been properly laterally adjusted, so that, when the cutter-support is rocked about its axis, the tooth in line with the grinding-face of said grinding-wheel is swung about the median line of its cutting-face.

For adjusting the cutter-head up and down on the cutter-support, I form the cutter-stem as an adjusting screw, which is 130

journalized in a bearing 93 in the tine 88, and provide the same with a knurled head 94 by which said adjusting screw is supported. The other end of the adjusting screw is threaded, as shown at 95, into the threaded bore of a bushing 97 slidable in a bearing 98 of the tine 89, the bushing being provided with a flange 99 from which a pin 100 extends into a hole 101 in the tine 89 for preventing turning of the bushing in its bearing and insuring, that when the adjusting screw is turned, axial movement of the bushing 97 will take place for raising or lowering the cutter received about the adjusting screw. Washers 102 may be received in suitable number about the stem under the cutter for proximate positioning of the cutter.

In order to gage the parts into positions for accomplishing the purposes stated, I provide a gage 105, shown as a rod having a straight-face 106 at one end which is coincident with the longitudinal axis of the rod, and a recess 107 at its other end having oppositely sloping walls 108, having equal angularity at opposite sides of the longitudinal axis of said rod. The gage is arranged to be placed in the bearing 109 of the cutter-support with its longitudinal axis coincident with the rocking axis of the cutter-support. The gage may be placed in this bearing with either of its ends projecting toward the grinding-wheel. This gage may be first placed with its straight-face projecting toward the grinding-wheel, as indicated in Fig. 7, and with the gage 84 preferably placed at zero, although this latter is not essential. The apron 27 is adjusted laterally on the slide-member 26, so that the straight-face 106, which has been previously placed in range with the grinding-wheel, will make contact with the grinding-face 19 of said grinding-wheel, thereby positioning the longitudinal axis of the bearings for the cutter-stem 90 in the plane of the grinding-face, the cutter-stem itself having been previously removed for permitting the rod 105 to pass the position normally occupied by said cutter-stem.

The cutter and cutter-stem having been positioned on the cutter-support, and the gage 84 being placed at zero, the cutter having teeth provided with cutting-faces which extend parallel to its axis of rotation will be so located, that the cutting-face of its tooth nearest the grinding-wheel is parallel to the plane of the grinding-face thereof, the back-stop having been properly adjusted. Upon reciprocation of the cutter-support toward and from the grinding-wheel, the tooth will be properly ground by the grinding-wheel, the teeth of the cutter being successively operated upon.

If it is desired to grind the teeth of a cutter having so-called staggered teeth, exem-

plified by the cutter 25' (Figs. 8 and 9), the cutter having been placed on the stem and the stem having been mounted on the cutter-support with sufficient washers 102 under the cutter to approximately position the middle of the cutting-face of the cutter in line with the rocking axis of the cutter-support, the gage 105 is placed in the bearing 109, with the recess 107 toward the cutter, as exemplified by the position of the gage 75 in Fig. 6. The cutter-stem 90 is now turned for raising the cutter to such position, so that the gage 105 can be pushed toward the cutter with equal contact of each of said sloping walls 108 with opposite sides of the teeth of the cutter. When such equal contact is had, the cutter will have been adjusted, so that the median line of the cutting-face of the tooth presented to the grinding-wheel will be coincident with the axis upon which the cutter-support turns.

The clamp-screw 87 is released for releasing the clamp-bearing 81, and the cutter-support is turned so that the graduation at one side of the zero mark, which corresponds to the desired degree of angularity of the cutting-face of the tooth to be ground, will register with the guide mark of said gage, the clamp-bearing being then again clamped. The cutting-faces of alternate teeth on the cutter to be ground will now be parallel and in line with the grinding-face of the grinding-wheel, when brought into grinding position, with the median line of the cutting-face being ground coincident with the rocking axis of the cutter-support. (See Figs. 8 and 9).

When the teeth having their cutting faces extending in similar directions have been ground, the clamp-bearing 81 is again unclamped, and the cutter-support turned for bringing its corresponding graduation at the opposite side of the zero mark in registry with the guidemark 86, and the clamp-bearing again clamped in place, whereby the teeth having their cutting-faces extending in the opposite direction will, when they are brought into juxtaposition with the grinding-face of the grinding-wheel, extend in the plane of said grinding-face with the median line of the cutting-face in line with the rocking axis of the cutter-support.

My improved device insures accurate grinding of the cutters, whether having cutting-faces which are plain or staggered, and provides a compact construction readily manipulated for accurately placing the cutters with their teeth in proper positions to be ground.

Having thus fully described my invention, what I claim as new and desire to secure by Letters Patent, is:

1. In a cutter grinder, the combination of a grinding-wheel having an end grinding-face, a cutter-support having a cutter axis,

said cutter-support rotatively adjustable on an axis intersecting said cutter axis and parallel to the plane of said grinding-face.

2. In a grinding machine, the combination of a grinding-wheel having an end grinding-face, a cutter-support having a cutter axis, said cutter-support adjustable on an axis located in the plane of said grinding-face substantially perpendicular to and intersecting said cutter axis.

3. In a cutter grinder, the combination of a grinding-wheel having a grinding-face, a cutter-support having a cutter axis adjustable about an axis intersecting said cutter axis and located in the plane of said grinding-face when the cutter is in grinding position, adjusting means for adjusting the cutter lengthwise of said cutter axis, and adjusting means for adjusting said second-named axis toward and from the plane of said grinding-face.

4. In a cutter grinder, the combination with a grinding-wheel having an end grinding-face, a cutter-support having a cutter-supporting stem, means for adjusting said cutter-support laterally with relation to said grinding-face, means for rotatively adjusting said cutter-support on an axis lying across said grinding-face, a gage provided with a gaging face for coacting with said grinding-face whereby to adjust the lateral position of said support, said support provided with a guide for said gage parallel to said axis on which said cutter-support is rotatively adjusted.

5. In a cutter grinder, the combination with a grinding-wheel having an end grinding-face, a cutter-support having cutter-supporting means thereon, means for adjusting the cutter lengthwise of its axis of rotation on said cutter-supporting means, means rotatively mounting said cutter-support on an axis lying across said grinding-face and intersecting said axis of rotation when said cutter is mounted on said cutter-supporting means, a gage provided with cutter-contacting faces, means for mounting said gage on said cutter-support with said cutter-contacting faces equal distances from said second-named axis whereby to gage the longitudinal adjustment of the cutter on said cutter-supporting means.

6. In a cutter grinder, the combination, with a grinding-wheel, of a cutter-support, means for causing right-line approach and recession between said grinding-wheel and cutter-support comprising a right-line guiding support, and means for rotatively adjusting said cutter-support on an axis substantially parallel to said right-line approach and recession and substantially perpendicular by said support to the axis of rotation of the cutter supported by said support.

65 7. In a cutter grinder, the combination,

with a grinding-wheel, of a cutter-support, means for causing right-line approach and recession between said grinding-wheel and cutter-support comprising a right-line guiding-support, means for rotatively adjusting said cutter-support on an axis located in a plane substantially parallel to the plane of said right-line approach and recession and substantially perpendicular to the axis of rotation of the cutter supported by said cutter-support, and means for adjusting said cutter on said cutter-support lengthwise of its axis of rotation with relation to said axis on which said cutter-support is rotatively adjusted.

8. In a cutter grinder, the combination, with a grinding-wheel, of a cutter-support, means for causing right-line approach and recession between said grinding-wheel and cutter-support comprising a right-line guiding-support, means for rotatively adjusting said cutter-support on an axis located in a plane substantially parallel to the plane of said right-line approach and recession and substantially perpendicular to the axis of rotation of the cutter supported by said cutter-support, means for adjusting said cutter on said cutter-support lengthwise of its axis of rotation with relation to said axis on which said cutter-support is rotatively adjusted.

9. In a cutter grinder, the combination of a refuse-pan, a grinding-wheel rotatable therein, a cutter-support in said refuse-pan, means for causing right-line approach and recession between said grinding-wheel and cutter-support comprising a right-line guiding-support outside the refuse-containing walls of said refuse-pan, and means for rotatively adjusting said cutter-support on an axis located in a plane substantially parallel to the plane of said right-line approach and recession and substantially perpendicular to the axis of rotation of the cutter supported by said support.

10. In a cutter grinder, the combination of a refuse-pan, a grinding-wheel rotatable therein, a cutter-support in said refuse-pan, means for causing right-line approach and recession between said grinding-wheel and cutter-support comprising a right-line guiding-support outside the refuse-containing walls of said refuse-pan, means for rotatively adjusting said cutter-support on an axis located in a plane substantially parallel to the plane of said right-line approach and recession and substantially perpendicular to the axis of rotation of the cutter supported by said cutter-support, and means for adjusting said cutter on said cutter-support lengthwise of its axis of rotation.

with relation to said axis on which said cutter-support is rotatively adjusted.

11. In a cutter grinder, the combination of a grinding-wheel, a bracket extending substantially parallel to the axis of rotation of said grinding-wheel, means for rotatively adjusting said bracket on an axis substantially parallel to said axis of rotation, a bearing on said bracket, a cutter-support journaled for adjustment in said bearing on an axis at substantial right angles to said first-named axis, means for causing endwise adjustment between said bracket and grinding-wheel, means for adjusting the cutter lengthwise of its axis of rotation on said cutter-support, said cutter-support provided with a gage having contact-faces for the cutter which recede equally in opposite directions from that plane parallel to the side faces of said cutter in which said journal axis of said cutter-support is located for determining said adjustments of said cutter lengthwise of its axis of rotation, and means for causing approach and recession between said grinding-wheel and bracket.

12. In a cutter grinder, the combination of a grinding-wheel, a bracket extending substantially parallel to the axis of rotation of said grinding-wheel, means for rotatively adjusting said bracket on an axis substantially parallel to said axis of rotation, a bearing on said bracket, a cutter-supporting yoke journaled for adjustment in said bearing on an axis at substantial right angles to said first-named axis, said yoke provided with a pair of tines between which the cutter is arranged to be received, a cutter-supporting stem journaled in one of said tines, and a bushing having sliding movement lengthwise of said stem in the other of said tines, said bushing arranged to support the cutter, and said stem having threaded connection with said bushing whereby to adjust said cutter in said yoke lengthwise of its axis of rotation.

13. In a cutter grinder, the combination of a grinding-wheel having an end grinding-face, a bracket extending substantially parallel to the axis of rotation of said grinding-wheel, means for rotatively adjusting said bracket on an axis substantially parallel to said axis of rotation, a bearing on said bracket, a cutter-support journaled for adjustment in said bearing on an axis at substantial right angles to said first-named axis, means for causing endwise adjustment between said bracket and grinding-wheel, said cutter-support having a straight-face gage thereon arranged for presenting said straight-face parallel to said grinding-face throughout the various rotative adjustments of said cutter-support for determining the endwise adjustments between said bracket

and grinding-wheel, and means for causing approach and recession between said grinding-wheel and bracket.

14. In a cutter grinder, the combination of a grinding-wheel having an end grinding-face, a bracket extending substantially parallel to the axis of rotation of said grinding-wheel, means for rotatively adjusting said bracket on an axis substantially parallel to said axis of rotation, a bearing on said bracket, a cutter-support journaled for adjustment in said bearing on an axis at substantial right angles to said first-named axis, means for causing endwise adjustment between said bracket and grinding-wheel, means for adjusting the cutter lengthwise of its axis of rotation on said cutter-support, a gage on said cutter-support provided with a straight-face at one end thereof for coaction with said grinding-face for determining the endwise adjustments between said bracket and grinding-wheel with oppositely receding contact-faces at the other end thereof for determining said adjustments of said cutter lengthwise of its axis of rotation, and means for causing approach and recession between said grinding-wheel and bracket.

15. In a cutter grinder, the combination of a grinding-wheel having an end grinding-face, a cutter-support, means for causing adjustment between said grinding-wheel and cutter-support lengthwise of the axis of rotation of said grinding-wheel, means for rotatively adjusting said cutter-support on an axis parallel to said grinding-face, means on said cutter-support for adjusting the cutter thereon lengthwise of its axis of rotation, and a gage on said support provided with a straight-face arranged to coact with said grinding-face for determining said first-named adjustment and with opposed contact-faces for the cutter spaced equally from said axis on which said cutter-support is rotatively adjusted for determining the adjustment of said cutter lengthwise of its axis of rotation.

16. In a cutter-grinder, the combination with a grinding-wheel, of a cutter-support having a cutter axis, said cutter-support rotatively adjustable on an axis intersecting said cutter axis in the plane of and lying across the grinding-face of said grinding-wheel when the cutter on said cutter-support is in grinding position.

In testimony whereof, I have hereunto signed my name in the presence of two subscribing witnesses.
